US00D999244S

(12) **United States Design Patent** (10) Patent No.: US D999,244 S
Indorf et al. (45) Date of Patent: ** Sep. 19, 2023

**(54) DISPLAY SCREEN OR PORTION THEREOF
WITH A GRAPHICAL USER INTERFACE**

5,319,355	A	6/1994	Russek
5,337,744	A	8/1994	Branigan
5,341,805	A	8/1994	Stavridi et al.

5,377,676	A	1/1995	Vari et al.
D359,546	S	6/1995	Savage et al.
5,431,170	A	7/1995	Mathews

(71) Applicant: **MASIMO CORPORATION**, Irvine,
CA (US)

(72) Inventors: **Keith Ward Indorf**, Lake Elsinore, CA (US); **Ammar Al-Ali**, San Juan Capistrano, CA (US)

(73) Assignee: **MASIMO CORPORATION**, Irvine,
CA (US)

FOREIGN PATENT DOCUMENTS

(**) Term: 15 Years

CN 104127181 11/2014
CN 104586398 5/2015
(Continued)

(21) Appl. No.: 29/773,988

OTHER PUBLICATIONS

U.S. PATENT DOCUMENTS

4860-128 A 10/1990 Gordon et al.

4,960,128 A 10/1990 Gordon et al.
 4,964,408 A 10/1990 Hink et al.

The sole FIGURE is a front view of a display screen or portion thereof with a graphical user interface showing our new design.

The broken lines, including those showing a display screen or portion thereof and those depicting portions of a graphical user interface, form no part of the claimed design.

DESCRIPTION

1 Claim, 1 Drawing Sheet
